UNITED STATES PATENT OFFICE.

FRED LOUDON, OF WILMINGTON, ILLINOIS.

SHOW-CASE.

1,123,332.

Specification of Letters Patent.

Patented Jan. 5, 1915.

Application filed January 20, 1914. Serial No. 813,208.

To all whom it may concern:

Be it known that I, FRED LOUDON, a citizen of the United States, residing at Wilmington, in the county of Will and State of Illinois, have invented certain new and useful Improvements in Show-Cases, of which the following is a specification.

The show case which is the subject matter of the present application for patent is designed more particularly for holding and displaying cigars, and the object of the invention is to provide a novel and improved show case structure which will obviate the necessity of taking a box of cigars out of the case and holding it before the customer for his choice.

A further object of the invention is to provide a show case having a novel and improved closure, and means whereby the same may be operated by the salesman behind the case.

The herein stated objects are attained by means of a novel combination and arrangement of parts to be hereinafter described and claimed, reference being had to the accompanying drawings, in which—

Figure 1 is a perspective view of the show case; Fig. 2 is a longitudinal section thereof; Fig. 3 is a rear end view, partly in section, and Fig. 4 is a horizontal section of one corner of the case.

Referring specifically to the drawings, 5 denotes the side walls of a case or housing, the same being stepped at the top to support a series of compartments in which the cigar boxes to be displayed are placed. The side walls may be paneled as shown, or otherwise constructed to produce a neat and attractive design, and they are connected by front and rear walls 6 and 7, respectively. The panels of the side walls are divided by posts 8, and the case also has corner posts 9 and a suitable base molding 10. It will be noted that the posts 8 and 9 are stepped in order that 45 the compartments may be arranged in steps or tiers, the rear compartment being the highest.

Each compartment comprises a bottom 11 suitably mounted and supported between the side walls 5, a top 12, a back 13, a vertically slideable front door 14, and end walls 15. The door is supported at the bottom by a cross-bar 16 extending and slidably mounted between the side walls 5, said cross-bar having a top groove in which the lower edge or bottom of the door seats. On the

inner surface of the side walls 5 are spaced guide strips 17 between which the cross-bar slides. The cross-bar being vertically slideable it will be evident that the door 14 may be opened and closed by actuating the cross-bar. The following means are provided for this purpose: To the cross-bar 16 is secured a depending link 18 which is connected at the bottom to a rocker-arm 19 made fast on a rock-shaft 20 supported in suitable bearings 21 carried by one of the side walls 5. The shaft 20 terminates close to the back wall 7 of the case and has thereat a crank-arm 22, the handle 23 of which projects through a curved slot 24 in said wall 7. Upon grasping the crank-handle 23 and swinging the same to the right, the shaft 20 is rocked in a direction to swing the arm 19 downward, and as said arm is connected to the cross-bar 16, the door 14 is slid down to uncover the front of the compartment and render the interior thereof accessible. A swing of the crank-handle in the opposite direction slides the door upward to closed position, the action being assisted by a counterweight 25 carried by a line 26 made fast to the extremity of the arm 19 and passing over a guide pulley 27 mounted on one of the side walls 5. The counterweight balances the parts so that the crank-handle may be released without the door dropping down. The door of each compartment has an independent operating mechanism as herein described.

It will be noted in Fig. 2 that the top 12 of the compartment is spaced at the back from its wall 13 a sufficient distance to accommodate the door of the next compartment to the rear. In the rear of each compartment, except the top one, is a wall 13^a which supports the rear portion of the top 12 of the compartment and is spaced from the wall 13 a sufficient distance to accommodate the door of the next compartment above. All joints of the compartment walls will be lined with felt strips to exclude air. The end and bottom edges of the doors 14 have a metal edge binding 29, as shown in Fig. 4, to prevent chipping, said doors being made of glass. The walls of the compartment are also made of glass in order to display the contents thereof. The side posts 8 and the front corner posts 9 have guide grooves 30 for the doors 13.

By means of the show case hereinbefore described the cigars can be displayed in a

safe, convenient and attractive manner, and it is not necessary for the salesman or clerk to reach into the case and hand out the cigars to the customer. This method is objectionable as the cigars are liable to damage by the repeated handling, and they must also be rearranged at frequent intervals. The sliding doors are readily operated by the salesman from his place behind the counter, and the customer, after the door of the compartment containing the desired brand of cigars has been opened, can reach into the same and select the cigar or cigars desired without removing the box.

15 I claim:

A show case comprising a housing, a series of compartments at the top of the housing arranged in stepped relation and comprising each a top, a bottom, and a rear wall, 20 the front of the compartment being open,

a door for the open front of each compartment, said door being slidable downward into the housing to uncover said front of the compartment, a series of rock shafts mounted in the housing below the compartments, and located adjacent to one of the side walls of the housing, one end of the shafts terminating adjacent to the back wall of the housing, said wall having slots, crank arms on the rock shafts having actuating handles projecting through the aforesaid slots, rocker arms extending from the rock shafts, and links connecting the rocker arms to the respective doors.

25 In testimony whereof I affix my signature 30 in presence of two witnesses.

FRED LOUDON.

Witnesses:

FRANK ROWLAND,
AMBROSE S. HADSALL.
